GARMENT PROTECTOR

Daniel Topjian, Watertown, Mass., assignor, by
mesne assignments, to himself, as trustee

Application September 29, 1942, Serial No. 460,073

6 Claims. (Cl. 2—53)

This invention relates to apparel and more especially to means for protecting garments from the injurious effects of perspiration and to prevent the unpleasant odors which usually develop when perspiration is absorbed by articles of apparel. While in its broader aspects the invention is useful in connection with other garments it is here illustrated and described, by way of example but without limiting intent, as embodied in a dress shield of the general type customarily located at the armpit portion of a dress.

Commonly dress shields are merely layers of absorbent material sometimes combined with a layer or layers of waterproof or moisture-resistant material and are intended by absorption of or resistance to the penetration of moisture, or both, to prevent perspiration from moistening, discoloring or imparting an unpleasant odor to the material of the dress itself.

While perspiration is a very dilute fluid, it does contain about 1% of solids including sodium chloride, nitrogenous compounds, fats, fatty acids, stearates, lymphoidal cells, cellular nuclei and cellular debris. Among the chemical substances recognized in human perspiration are acetic, propionic, caproic, caprylic, butyric, lactic and ascorbic acids and traces of uric acid.

Normally, as secreted, perspiration has a slight though not necessarily unpleasant odor, but when exposed to moisture and warmth the various residue materials and especially the fats, fatty acids, etc., undergo decomposition and chemical changes, often resulting in a very offensive odor. Under some pathological conditions the perspiration, even when first secreted, may have a disagreeable odor.

Various preparations have been proposed for reducing the amount of perspiration secreted. Usually such preparations are of an astringent nature, compounds of aluminum being commonly employed, but such substances, if used habitually, are believed to exert a harmful effect, and many of these compounds are injurious to clothing.

On the other hand, it has been proposed to apply, either directly to the skin or to the garment of the wearer, various deodorizing or perfuming substances designed to suppress or overpower the perspiration odor, and while to a cer-

tain extent effective, such a procedure has little appeal to the really fastidious person.

Among the objects of the present invention are to provide a garment protecting means of improved type comprising a perspiration-absorbing element which is so cheap and easily replaceable as to make it reasonably certain that the user will discard it before it becomes ineffective for its intended purpose; to provide a replaceable absorbing element of ample capacity (which may be supplied to the user in units of different capacity if desired); to provide a garment protector, for specific example a dress shield, comprising a compartment or compartments for the reception of such an absorbent element and so designed that the walls of such compartment will not themselves become permeated with perspiration even during a long period of use; to provide a replaceable absorbent element containing a substance capable of opposing any tendency of the absorbed perspiration, in particular the fats and fatty constituents of the perspiration, to become disagreeably odoriferous but which is so separated from the skin and from the material 5 of the garment itself that it cannot cause injury to either; and to provide a protecting device having means whereby it may removably be secured to a garment, thereby reliably to hold it in proper position while at the same time to permit its ready removal for replacement of the 10 perspiration-absorbent elements.

Other and further objects and advantages of the invention will be pointed out in the following more detailed description and by reference to 15 the accompanying drawing, wherein

Fig. 1 is a perspective view showing the outside of the shield as it is actually used and showing, in enlarged diagrammatic elevation, a type of fabric which is desirable for use as the outer 20 element of the shield;

Fig. 2 is a view similar to Fig. 1 but showing the shield inside out, a portion of the inner wall of the shield being broken away to indicate the 25 absorbent filler member;

Fig. 3 is a section, substantially on the line 3—3 of Fig. 1, to somewhat larger scale;

Fig. 4 is an elevation, with certain parts broken away, illustrating a composite filler leaf or pad useful with the improved shield;

Fig. 5 is a similar elevation of a simple, multi-ply filler leaf or pad of different construction;

Fig. 6 is a section on line 6-6 of Fig. 5;

Fig. 6a is a fragmentary edge elevation to large scale of the filler leaf of Fig. 5;

Fig. 7 is a fragmentary section, to small scale, showing how the improved shield may be applied to the arm-scye of a garment;

Fig. 8 is an inside elevation of a pad holder of modified form; and

Fig. 9 is an elevation of a removable pad for use with the holder of Fig. 8.

Referring to the drawing, the improved shield of the present invention, as illustrated in Fig. 1, comprises a holder including a pair of similar more or less lune-shaped wings 1 and 2 hinged together along their concave edges 3. These wings are of multi-ply construction, each wing having an interior pocket for the reception of a removable, leaf-like absorbent pad hereinafter more fully described.

Referring to Fig. 3, the wings 1 and 2 are shown as comprising the outer members 4 and 4a, respectively, said outer members being of flexible material, for example a textile fabric, and preferably of a more or less loose or open mesh so as to make them readily pervious to moisture. Thus, as illustrated at E, (Fig. 1) this outer ply or layer may consist of fabric knitted in the so-called "eyelet" pattern, a construction which provides a soft, flexible and thin material having definite openings of more or less rectangular contour. While this is a desirable type of fabric, other materials such as net fabrics or the like may be employed, and, in fact, any soft, flexible and thin material provided with pores, apertures or perforations is acceptable for the purpose even including sheet rubber (when available) provided with a multitude of small perforations. If textile material be employed, it is desirable to treat it in such a way as to make the material itself substantially non-absorbent of moisture if by reason of its actual characteristics it is non-absorbent. Rayon fabrics untreated may be satisfactory for the purpose since they do not readily absorb moisture into their fibrous structure, but fabrics of cotton or the like should be so prepared as to waterproof their constituent yarns, as by coating or preferably impregnation with some of the well known waterproofing compounds such, for example, as are used in making rainproof or rain-resistant fabrics.

Each of the wings 1 and 2 also comprises an inner member 5 and 5a, respectively, said inner members being soft and flexible but of a material which is substantially impervious to the passage of moisture through the thickness of the material. While thin sheet rubber may be employed for the purpose, if available, it is contemplated that textile fabric having this inherent characteristic, or textile fabric frictioned with rubber or otherwise treated to make it waterproof by the application of any appropriate treating material may be used.

The concave edges of the outer members 4 and 4a are permanently and flexibly united by a sewed seam at 6. The members 4 and 5 of the wing 1 are united by marginal stitches 7, while the members 4a and 5a of the wing 2 are united by marginal stitches 8, it being noted, however, that the upper edges 11 and 11a of the members 5 and 5a are left free, thus providing entrances to the spaces or pockets 10 and 10a, respectively, between the members 4 and 5 and the members 4a and 5a.

Closure flaps 12 and 12a, also of moisture-imperious material, are attached at their upper edges, preferably by the same sewing stitches 6 which unite the members 4 and 4a. The lower edges of these impervious closure flaps 12 and 12a depend freely into the upper portions of the pockets 10 and 10a, forming in effect continuations of the inner walls 5 and 5a of the pockets above the points 11 and 11a and terminating at the points 13 and 13a, respectively, at a substantial distance below the edges 11 and 11a.

The pockets 10 and 10a are designed removably to hold absorbent pads 14 and 14a, respectively, said pads being thin, flexible and leaf-like in general character. When installed in the respective pockets, these pads project up beyond the lower edges 13 and 13a of the closure flaps, the lower portions of the flaps thus being interposed between the filler pads and the inner walls 5 and 5a of the respective wings. As previously made, most dress shields have been inadequate to absorb the perspiration completely, with the result that lingerie and dress fabrics, from repeated wettings, are permanently discolored and weakened so that garments, otherwise capable of much longer wear, must be discarded by reason of such under-arm damage. In accordance with the present invention, it is proposed to provide removable absorbent pads of different capacity to meet the needs of each individual user, but all equally applicable to the shield device herein disclosed.

As illustrated in Fig. 4, the filler pad or leaf 14 consists of two outer plies 15 of thin, porous reinforce material, for example cheesecloth, having interposed between them a layer 16 of absorbent material which is held securely in place by stitches 17 which unite the plies 15 along their edges. The absorbent layer 16 may be of any suitable character, for example other plies of the same material as the outer plies; a layer of cotton batting; a layer or layers of soft absorbent paper; felted cellulose fiber, or, in fact, any substance which readily absorbs moisture.

In Figs. 5 and 6 a modified and simpler filler pad or leaf is illustrated consisting of a sheet or sheets of material similar to the layer 16 above described. Thus, as shown in Fig. 5, the pad 17 consists of thin absorbent paper stock which, as indicated in Fig. 6, may be disposed in a plurality of parallel plies or films 17a. This material 17 may, for example, be of the type employed for making paper diapers or similar absorbent articles, being sufficiently shape-retentive to hold its shape without reinforcement when disposed in the pockets of the shield. Whether the pad be like that of Fig. 4 or Fig. 5, the absorbent layer may be of as many plies as desired to provide the requisite moisture-absorbent capacity, and these pads may be supplied to the trade having two, four, eight or more absorbent plies.

As illustrated in Fig. 6a, the filler pad, whether of the type illustrated in Fig. 4 or in Fig. 5, is preferably impregnated with a substance which tends to inhibit bacteriological or chemical change in the solid residue of the perspiration (particularly the fatty substances) which is absorbed by the pad. By the employment of such a substance, it is unnecessary to interfere with the free secretion of perspiration or, on the other hand, to try to conceal the disagreeable odor of perspiration by some overpowering perfume, since by this procedure the development of unpleasant odor is largely prevented. At the same time the material employed for inhibiting the development

of the odor is kept out of direct contact with the skin so that it is not liable to cause irritation to the skin and is wholly separated from the fabric of the garment so that there is no danger of discoloration or other injury to the garment. Among the materials which may be employed for impregnating the filler pad are 2,2'-dihydroxy 3,5,6,3',5',6'-hexachloro diphenyl methane, or benzoic acid compounded with sodium benzoate and boric acid. Obviously, if desired, some faint and delicate perfume may be incorporated, merely to impart a pleasant fragrance.

A filler pad designed and treated as above described is antiseptic and odor inhibiting and may be depended upon to absorb a very substantial quantity of the solids from perspiration before it loses its efficiency. However, when it has been used for so long a period as to have become clogged with deposited solids, it is very easily removed from the shield merely by pulling out the free edge of the closure flap from behind the upper edge 11 or 11^a of the inner walls of the wings, thus giving access to the pad which may be removed and replaced by a fresh pad. Since these pads may be made very cheaply, it is contemplated that they will be changed as frequently as may be desired and before through use they have become ineffective as absorbent elements.

In order to facilitate the application of this shield to the arm-scye of a garment, it is proposed to provide the inner walls 5 and 5^a with fastener elements 18, for instance the socket elements of snap fasteners, with the understanding that the complemental elements will be applied to the lining of the sleeve and garment as indicated in Fig. 7.

In the modified arrangement of Figs. 8 and 9, the moisture-resistant holder portion 20 of the shield comprises two wings 21 and 22 (each of moisture-impervious material and which may be single ply if desired) connected at 23, and designed to be permanently secured to the garment. The removable pad 24 may be similar in construction to the pads above described, but is preferably of a contour similar to that of the holder 2. Complemental snap fastener elements 28 and 28^a on the holder and pad respectively removably unite the pad to the outer side of the holder.

While certain desirable embodiments of the invention have been indicated by way of example, it is to be understood that the invention is not necessarily limited to these precise embodiments but is to be regarded as broadly inclusive of any and all modifications within the scope of the appended claims.

I claim:

1. A protective shield for use in the arm-scye of a garment, said shield comprising a pair of substantially lune-shaped wings flexibly united along their concavely curved edges, each wing being constructed and arranged to constitute a pocket for the reception of a removable absorbent pad, each wing having an inner wall of a material which is resistant to the passage of moisture and an outer wall of open mesh textile material having little or no capacity for absorbing moisture, the inner wall being so constructed and arranged as to provide free overlapping portions defining an opening giving access to the pocket, and a removable leaf-like pad of absorbent material disposed in each pocket, each pad containing a substance including benzoic acid and boric

acid operative to inhibit the evolution of disagreeable odors from absorbed perspiration.

2. A protective shield for use in the arm-scye of a garment, said shield comprising a pair of substantially lune-shaped wings flexibly united along their concavely curved edges, each wing being constructed and arranged to constitute a pocket for the reception of a removable leaf-like pad of absorbent material, each wing having an inner wall of a material which is resistant to the passage of moisture and an outer wall of soft, flexible pervious material which has little or no capacity for absorbing moisture, means uniting the inner and outer walls along their outer edges, the inner wall of each wing comprising parts having juxtaposed relatively movable free edges which are separable thereby to provide access to the respective pockets.

3. A protective shield for use in the arm-scye of a garment, said shield comprising a pair of substantially lune-shaped wings flexibly united along their concavely curved edges, each wing being constructed and arranged to constitute a pocket for the reception of a removable absorbent pad, each wing having an inner wall of a material which is resistant to the passage of moisture and an outer wall of pervious but non-absorbent textile material, the inner wall of each pocket comprising overlapping free portions to afford access to the pocket, each pocket being designed to receive a leaf-like pad of absorbent material of a contour generally similar to that of the wing, and a fastener element exposed at the lower part of the inner wall of each wing and designed for engagement with a complemental fastener element secured to the garment.

4. A dress shield comprising a pair of substantially like wings and means permanently and flexibly uniting said wings along their upper edges, each wing including an outer body-contacting wall of open mesh textile fabric made from water-impervious yarns and an inner garment-contacting wall of a material which is impervious to and non-absorbent of moisture, the inner wall of each wing comprising lower and upper parts, the upper edge of the lower part and the lower edge of the upper part being free but normally overlapping, and a thin, flexible removable filler pad of substantially uniform thickness and of bibulous material interposed between the inner and outer walls of each wing, said filler pads being removable at will by withdrawing them from between the normally overlapped free edges of the upper and lower portions of the inner wall of the wing.

5. A dress shield comprising a pair of substantially like wings and a sewed seam permanently uniting said wings along their upper edges, each wing including an outer wall and an inner wall, means permanently uniting the outer and inner walls of each individual wing along the side and bottom edges of the respective wing, the outer wall of each wing being moisture-pervious but substantially non-absorbent of moisture and the inner wall of each wing being impervious and non-absorbent, the inner wall of each wing comprising lower and upper portions, the upper edge of the upper portion of the inner wall being anchored by the seam which unites the wings and the lower edge of the upper portion of the inner wall being free and normally overlapping the upper free edge of the lower portion of the inner wall, the outer and inner walls of each wing respectively defining a pocket access to which may be obtained by separating the overlapping edges

of the upper and lower portions of the inner wall of the wing, and a removable leaf-like pad of bibulous material normally disposed in each pocket.

6. A protective shield for use in the arm-scye of a garment, said shield comprising a pair of substantially lune-shaped wings flexibly united along their concavely curved edges, each wing being constructed and arranged to constitute a pocket for the reception of a removable absorbent pad, each wing having an inner wall of a material which is resistant to the passage of moisture and an outer wall of open mesh textile

material having little or no capacity for absorbing moisture, the inner wall being so constructed and arranged as to provide free overlapping portions defining an opening giving access to a pocket, and a removable leaf-like pad of absorbent material disposed in each pocket, each pad being lune-shaped and consisting of a highly absorbent multi-ply layer of cellulosic material impregnated with a substance operative to inhibit the evolution of disagreeable odors from absorbed perspiration.

DANIEL TOPJIAN.
